UNITED STATES PATENT OFFICE.

EDWARD SUSMAN, OF PITTSBURG, PENNSYLVANIA.

UMBRELLA DRIP-CUP.

SPECIFICATION forming part of Letters Patent No. 288,889, dated November 20, 1883.

Application filed June 13, 1883. (No model.)

To all whom it may concern:

Be it known that I, EDWARD SUSMAN, of No. 28 Wylie avenue, Pittsburg, Pennsylvania, have invented a new and useful Improvement 5 in Water-Drip Cups for Umbrellas, which improvement is fully set forth in the following specification, reference being had to the accompanying drawings.

Similar letters of reference indicate corresponding parts.

My invention relates to a method of collecting the water from an umbrella or parasol by means of an adjustable flexible cup fixed to the end of the handle, as will be more fully described hereafter.

In the accompanying drawings, Figure 1 is a representation of an umbrella when hoisted. Fig. 2 is a representation of the same when closed, and shows a sectional view of the cup. 20 Fig. 3 shows the umbrella closed, and neatly folded up with the cup in place and closely folded up; and Fig. 4 is a representation of my water-cup detached from the umbrella.

In the drawings, A is the body of the umbrella. A' is the handle. B is the water-cup. 25 b is the attaching-sheath. b' is a cord to secure to the cup B a wrapping-ring, b². b³ is a ring on the periphery of the cup for strength. The cup B is made bell shape with the sheath 30 b to affix the cup to the ferrule end of the handle. This sheath b will be made to fit closely around the end of the handle, so tightly that it will not come off of its own gravity nor when filled with water. The cup will be made 35 of an elastic material, so that it will not only spread, as seen in Fig. 1, but be susceptible of being rolled up, as seen in Fig. 3. This cup may be carried in the pocket, or it may be fixed to the inside of the umbrella by any 40 suitable means, and in this way folded up, as it readily can be, by reason of its flexibility;

or the cup may be left on the umbrella and folded over itself by means of the ring b², as seen in Fig. 3.

The utility of such a contrivance for catching the water from an umbrella will readily be understood. Very often on entering a room, church, store, or dwelling with an umbrella soaked with water, no convenient place is found to catch the dripping water from it. It 45 is not safe to leave the umbrella out of your hands, as the experience of mankind will verify, and to have a receptacle such as the cup B would undoubtedly be of great use, as you can in most cases keep hold of it yourself, 50 which is the safer way. The most common place to put a dripping umbrella is in a spittoon. This is generally a nauseous place to stick it. As to the "umbrella-rack" generally found in hall-ways, a great difficulty is experienced in taking the water-drippings of 55 umbrellas from them, they being unwieldy and hard to handle.

For the purposes of my invention I deem the foregoing description as to the invention and 60 its utility sufficient to enable others to make and use the same, at least full enough to satisfy the demands of the patent law.

Having thus described my invention, what I claim, and desire to secure by Letters Patent, 65 is—

In an umbrella drip-cup, B, the bell-shaped cup B, having the sheath b, ring b³, cord b', and ring b², substantially as described and shown.

In testimony that I claim the foregoing as my invention I hereto set my hand in the presence of two witnesses.

EDWARD SUSMAN.

Witnesses:

R. COM. BARRIS,
JOHN HARVEY.
